(57) **CLAIM**

The ornamental design for a display screen with animated graphical user interface, as shown and described.

DESCRIPTION

FIG. 1 is a front view of a first image in a first sequence of a display screen with animated graphical user interface showing our new design;

FIG. 2 is a front view of a second image thereof;

FIG. 3 is a front view of a first image in a second sequence of a display screen with animated graphical user interface showing our new design;

FIG. 4 is a front view of a second image thereof;

FIG. 5 is a front view of a third image thereof;

FIG. 6 is a front view of a first image in a third sequence of a display screen with animated graphical user interface showing our new design;

FIG. 7 is a front view of a second image thereof;

FIG. 8 is a front view of a third image thereof;

FIG. 9 is a front view of a first image in a fourth sequence of a display screen with animated graphical user interface showing our new design;

FIG. 10 is a front view of a second image thereof;

FIG. 11 is a front view of a third image thereof;

FIG. 12 is a front view of a first image in a fifth sequence of a display screen with animated graphical user interface showing our new design;

FIG. 13 is a front view of a second image thereof;

FIG. 14 is a front view of a third image thereof;

FIG. 15 is a front view of a fourth image thereof;

(Continued)

FIG. 16 is a front view of a first image in a sixth sequence of a display screen with animated graphical user interface showing our new design;
 FIG. 17 is a front view of a second image thereof;
 FIG. 18 is a front view of a third image thereof;
 FIG. 19 is a front view of a fourth image thereof;
 FIG. 20 is a front view of a fifth image thereof;
 FIG. 21 is a front view of a first image in a seventh sequence of a display screen with animated graphical user interface showing our new design;
 FIG. 22 is a front view of a second image thereof;
 FIG. 23 is a front view of a first image in an eighth sequence of a display screen with animated graphical user interface showing our new design;
 FIG. 24 is a front view of a second image thereof;
 FIG. 25 is a front view of a third image thereof;
 FIG. 26 is a front view of a first image in a ninth sequence of a display screen with animated graphical user interface showing our new design;
 FIG. 27 is a front view of a second image thereof;
 FIG. 28 is a front view of a first image in a tenth sequence of a display screen with animated graphical user interface showing our new design;
 FIG. 29 is a front view of a second image thereof;
 FIG. 30 is a front view of a third image thereof;
 FIG. 31 is a front view of a first image in an eleventh sequence of a display screen with animated graphical user interface showing our new design; and,
 FIG. 32 is a front view of a second image thereof.
 The outermost broken lines illustrate a display screen and form no part of the claimed design. The remaining broken lines, including all text, illustrate portions of the graphical user interface that form no part of the claimed design.
 The appearance of the animated graphical user interface transitions sequentially renumbered between the images shown in FIG. 1-2; 3-5; 6-8; 9-11; 12-15; 16-20; 21-22; 23-25; 26-27; 28-30; or 31-32. The process or period in which one image transitions to another image forms no part of the claimed design.
